CHARLES G. POLLEYS, OF PROVIDENCE, RHODE ISLAND, ASSIGNOR OF ONE-HALF TO
RALPH J. REGNIER, JR., OF PROVIDENCE, RHODE ISLAND

FOLDING CUSHION SEAT

Application filed January 12, 1929. Serial No. 332,060.

- This invention relates to an improved construction of folding cushion seat; and has for its object to provide a seat of this character which comprises a cover member 5 to the under side of which is connected a flexibly yieldable or foldable spacer member, the cover member being adapted to be folded about the spacer member when contracted to serve as a container therefor.
- 10 A further object of the invention is to form the spacer in ring shape and loosely connect the ring by means of loop members or other suitable means to the under side of the cover member, whereby the side edges 15 of the cover member may be folded around the sides of the spacer to inclose the same, thereby forming a practical and yet inexpensive seat of a size to be readily carried about in the pocket of the user to be readily unfolded and positioned for use and again 20 folded after using for convenient transportation.

With these and other objects in view, the invention consists of certain novel features 25 of construction, as will be more fully described, and particularly pointed out in the appended claims.

In the accompanying drawings:

Fig. 1 is a top view of the seat showing 30 the cushion spacer beneath.

Fig. 2 is a view of the under side of the seat when in extended position.

Fig. 3 is a section on line 3—3 of Fig. 2, 35 showing the seat in extended position with the cushion member resting on a base and a cover member resting upon the cushion.

Fig. 4 is a view showing the seat as partially folded with its side edges turned 40 downwardly and the rope or strip form of cushion suspended by loops from the side edges of the cover.

Fig. 5 is a bottom view showing the cover 45 as folded about the spacer, the sides of the latter being drawn inward toward each other.

Fig. 6 is a section on line 6—6 of Fig. 5.

Fig. 7 is a perspective view showing the 50 cover folded about the spacer member, the latter having its sides pressed into oblong shape about which the sides of the cover

are folded to form a container for the spacer.

Fig. 8 is a view of the under side of the cover member showing the spacer as being supported both on the sides and ends of the cover member by loop members which 55 loosely engage the spacer and serve to centralize it in the cover when the latter is folded over the spacer.

Fig. 9 is a section on line 9—9 of Fig. 8 showing the end loops as loosely embracing 60 the spacer member.

Fig. 10 is an edge view of my improved seat, showing the spacer as formed of corrugated material.

It is found by those attending outdoor sports, such as base-ball games, foot-ball games, picnics and the like, that often the only place to sit is upon the ground or upon hard, cold cement which in some instances, besides being uncomfortable, soil the clothing of the user, and that it is of advantage to provide an inexpensive readily foldable portable seat which may be folded into such shape that it may be readily carried about in the pocket of the user to be readily removed, unfolded and positioned for use, and to accomplish this in a simple and effective way, I have provided a portable seat having a foldable cover member which may be formed of any suitable material 65 such as cardboard, leather and other material and attach a spacer member to the under side of the foldable cover to raise the user from the supporting base, the cover member being adapted to be folded about 70 the spacer when collapsed or contracted to serve as a container for the same and then readily extended to serve as a soft and comfortable cushion seat to space the body of the person a suitable distance above the supporting base on which the seat rests; and the following is a detailed description of the present embodiment of my invention, showing one construction of portable cushion seat by which these advantageous results may be accomplished:

With reference to the drawings, 10 designates the cover member of the seat which may be formed of any suitable material such as cardboard, vulcanized fibre, baki-

lite and the like, the sides of which may be creased as at 11 or hinged to permit the same to be readily folded about the cushion spacer.

5 The spacer member 12 may be in any convenient shape or form and constructed of any suitable material, that herein shown being a tubular casing or skin filled with sawdust or other granular material and 10 with the ends of the tubing connected together forming a foldable or collapsible spacer member in ring form. This spacer member, however, may in some instances be in rope or strip form, that is a cushion of 15 extended length and of relatively small diameter in cross section, arranged in any suitable form to serve as a spacer to prevent the body from setting directly upon the supporting base such as the cold, wet 20 ground, cement or board seats.

The spacer or cushion may be formed in ring shape, in U-shape or of a plurality of sections laid parallel or otherwise and secured to the under side of the cover member. This spacer or cushion may be connected by any suitable means to the cover member but I preferably provide a pair of flexible side loops 13 which engage opposite sides of the ring-shaped spacer, the outer 25 edges 14 of these loops being secured to the side edges 15 of the cover member, whereby when it is desired to fold the seat, it is only necessary to turn the seat upside down, in which case the spacer rests upon the under 30 portion of the cover member, and fold the side portions of the cover in their creases or hinges about the spacer, as shown in Figs. 5, 6 and 7, to serve as a container for the casing and provide a convenient package 35 40 which may be readily slipped into the pocket of the user.

In some instances, in addition to the loops 13 embracing the sides of the spacer I may provide end loops 16 which will permit endways elongating of the ring-shaped spacer when its sides are contracted or forced inwardly toward each other to permit the edges of the cover member to be folded about the same, which end loops will then 45 50 centralize the cushion member in its cover and prevent it from slipping endwise thru the folded container.

In some instances, the spacer member may be formed of corrugated material as illustrated at 17 in Fig. 10, in which case the cover member will be creased or hinged lengthways of the corrugations permitting the whole to be folded into a compact space to be carried about in the pocket of the 55 60 user. I also in some instances, as shown at 18 in Fig. 7, may provide a fastening band 18 for holding the package in folded condition.

My improved portable foldable cushion seat is very inexpensive in construction, is

very practical in its operation in that it serves as a soft and comfortable seat and may be readily folded into small space and carried about in the pocket of the user.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A portable cushion seat comprising a cover having substantial rigidity to support the body of the user and having creases therein to permit folding, a support beneath said cover being flexible to be collapsed, means for loosely connecting said support to said cover, the cover being foldable along said creases about the support when the same is collapsed to serve as a container therefor.

2. A portable cushion seat comprising a cover having substantial rigidity to support the body of the user and having parallel creases therein to permit the same to be folded, a ring-shaped cushion being flexible to be collapsed, loops loosely connecting said ring cushion to the under side of said cover, the cover being foldable along said creases about the cushion when the cushion is collapsed to serve as a container therefor.

In testimony whereof I affix my signature.

CHARLES G. POLLEYS.
